(57) **CLAIM**

The ornamental design for a cosmetic product case, as shown and described.

DESCRIPTION

FIG. 1 is a bottom perspective view of a design for a cosmetic product case;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view thereof;

FIG. 9 is a front view thereof showing a cap thereof removed from a base thereof, where the cosmetic product case is shown as containing an unclaimed cosmetic product in the form of lipstick, which is shown by way of example;

FIG. 10 is a front exploded view thereof showing the cap removed from the base, with an unclaimed cosmetic product; and,

FIG. 11 is a bottom perspective exploded view thereof showing the cap removed from the base, with an unclaimed cosmetic product.

Any broken lines showing portions of the design are for illustrative purposes or to show environmental structure or boundaries that form no part of the claimed design.
